US0D1081579S

(12) **United States Design Patent** (10) **Patent No.:** **US D1,081,579 S**
(45) **Date of Patent:** **** Jul. 1, 2025**

(54) **POWER ADAPTER**

(71) Applicant: **Dongguan Wontravel Electric Co., Ltd, Dongguan (CN)**

(72) Inventor: **Liangguan Lin, Shenzhen (CN)**

(**) Term: **15 Years**

(21) Appl. No.: **29/919,232**

(22) Filed: **Dec. 1, 2023**

(51) **LOC (15) Cl. 13-03**

(52) **U.S. Cl.**

USPC **D13/137.2**

(58) **Field of Classification Search**

(57) **CLAIM**

The ornamental design for a power adapter, as shown and described.

DESCRIPTION

FIG. 1 is a front elevation view of a power adapter showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof; and,

FIG. 8 is another perspective view thereof.

1 Claim, 8 Drawing Sheets
